UNITED STATES PATENT OFFICE.

LOUIS SANDERS, OF NEW YORK, N. Y.

CARTRIDGE-BELT.

SPECIFICATION forming part of Letters Patent No. 621,148, dated March 14, 1899.

Application filed December 30, 1898. Serial No. 700,733. (No model.)

To all whom it may concern:

Be it known that I, LOUIS SANDERS, of the city of New York, borough of Brooklyn, in the county of Kings and State of New York, have invented a new and Improved Cartridge-Belt, of which the following is a full, clear, and exact description.

The object of the invention is to provide a clamp especially adapted to form a cartridge-receiving loop in a cartridge-belt, the clamp being so constructed that after it has once been placed in position it cannot be displaced under ordinary usage.

Another object of the invention is to provide a clamp for forming pockets in the extension-leaves of cartridge-belts and that may be utilized to increase or to decrease the diameter of a cartridge-pocket originally formed in a belt, the clamp being substituted for the separating or divisional devices originally employed, the clamp being also capable of use as an accessory to the original separating or divisional devices.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a front elevation of a portion of the improved cartridge-belt, a part thereof being in vertical section, the section being on the line 1 1 of Fig. 2. Fig. 2 is a plan view of the belt shown in Fig. 1, sundry of the pockets being empty and the others provided with cartridges. Fig. 3 is a vertical section on the line 3 3 of Fig. 1; and Fig. 4 is a detail perspective view of the clamp employed, the clamp being drawn on a larger scale than shown in the other views; and Fig. 5 is a perspective view of a modified form of clamp employed in connection with the loop-leaves of cartridge-belts.

A represents a belt, and B loop-leaves projected from the belt, being either integral with the belt or attached thereto. These loop-leaves may be formed into one or more pockets C for the reception of cartridges E or other articles, which is accomplished by the application of one or more clamps D to the

said loop-leaves. The clamps are preferably constructed of spring metal and include two opposing and properly-spaced side members 55 10, connected at the top and at the bottom by end members 11, and when the clamp is applied to a loop-leaf indentations 12 are made in the said top and bottom members in order to effect a firm binding engagement between 60 the top and bottom of the clamp and the corresponding edges of the loop-leaf to which the clamp is applied. The construction of the clamp is completed by the formation of inwardly-extending spurs 13, produced in the 65 side members 10. These spurs are preferably struck out from the material of the clamp, but may be attached thereto, if desired, and the preferred arrangement of the spurs is such that the spurs of one side member 70 will intervene those upon the opposing side member, as shown in Fig. 4.

When a clamp is to be applied to a loop-leaf, its side members are usually sprung outward, as illustrated in dotted lines at D' in 75 Fig. 4, and after the clamp is in place the spurs are upset by applying pressure to the outer surfaces of the side members of the clamp in any approved manner.

When the clamp is applied to the loop-leaf 80 of a belt—for example, as above set forth—it is firmly anchored or secured in position, and it is evident that the clamp may be adjusted at any desired point upon the belt prior to upsetting the spurs or causing them to engage with the members of a leaf. The improvement provides a simple and economic device especially adapted to form pockets in the loop-leaves of military or cartridge belts or for analogous purposes. 85 90

In Fig. 5 I have illustrated a modified form of the clamp in which I employ a single strip 14, the said strip being provided with spurs 15, that extend from opposite sides, preferably in a horizontal direction. These spurs 95 15 may be attached to the strip 14, or they may be struck out from the strip, as in practice may be found most desirable.

In the application of the modified form of clamp the strip 14 is introduced between the 100 members of a loop-leaf, and pressure is brought to bear simultaneously upon opposite sides of the loop-leaf where the clamp is applied to effect an entrance of the spurs into

the members of the loop-leaf and likewise a clamping engagement between the spurs and the outside faces of said loop-leaves.

Having thus described my invention, I 5 claim as new and desire to secure by Letters Patent—

1. A clamp for belt-leaves comprising the box-loop fitted to embrace the belt-leaf and having opposite connected arms arranged to 10 be outwardly bowed, and spurs or prongs arranged to be forced through the belt-leaf when the arms of the box-loop are readjusted to clamp the belt-leaf, substantially as set forth.

15 2. A clamp for belt-leaves consisting of the box-loop embracing the belt-leaves and having its opposite side arms connected at their ends and arranged to be bowed outwardly between the said ends, and having such arms pro-

vided with inwardly-projected spurs or prongs, 20 such spurs or prongs being arranged at comparatively considerable distances from the ends of the loop whereby they will not engage the belt-leaf when the clamp has its arms outwardly bowed, thereby permitting the application of the pronged box-loop to the belt-leaf, substantially as set forth. 25

3. A belt having loop-leaves and provided with a clamp by which to divide said leaf into pockets, such clamp consisting of a plate provided with spurs or prongs whereby it can be positively locked to the belt-leaf in any position desired, substantially as set forth. 30

LOUIS SANDERS.
